UNITED STATES PATENT OFFICE.

MAX KLEIN, OF NEW YORK, N. Y., ASSIGNOR TO SHAPIRO & ARONSON, INC., A CORPORATION OF NEW YORK.

DESIGN FOR A CANDLE TABLE LAMP.

Application filed January 25, 1924. Serial No. 8,407. Term of patent 7 years.

To all whom it may concern:

Be it known that I, MAX KLEIN, a citizen of the United States, residing at New York, in the county of New York and State of New York, have invented a new, original, and ornamental Design for Candle Table Lamp, of which the following is a specification, reference being had to the accompanying drawing, forming part thereof,

Fig. 1 is a side elevation.

Fig. 2 is a plan view of base showing the contour thereof in diagrammatic form.

I claim:

The ornamental design for a candle table lamp, as shown.

MAX KLEIN.
